UNITED STATES PATENT OFFICE.

DOLPHUS TORREY, OF NEW YORK, N. Y.

AUTOMATIC CAR-BRAKE.

SPECIFICATION forming part of Letters Patent No. 276,930, dated May 1, 1883.

Application filed June 29, 1882. Renewed April 13, 1883. (No model.)

To all whom it may concern:

Be it known that I, DOLPHUS TORREY, of the city, county, and State of New York, have invented a new and useful Improvement in 5 Automatic Car-Brakes, of which the following is a specification.

My invention relates to double-acting momentum-brakes, which are actuated by the draw-bar of the car, and have a reversible adjustment actuated by changes in the direction of wheel rotation. I also gage the intensity of brake application by the weight of the car and maintain a fixed proportion between the two. I also use an auxiliary mechanism, by 10 means of which, should there be a breakage of the car-coupling, I secure the instant application of the momentum-brakes upon all of the detached cars. It is my intention to embody this emergency-brake mechanism, in its 15 application to brake apparatus generally and as a distinct invention, in a separate application for Letters Patent, and the right so to do I hereby reserve to myself.

The object of my invention is to secure by 20 these means a more serviceable brake apparatus than has been heretofore used.

In the accompanying drawings, Figure 1 is a bottom view of one end of the bed-frame of a car, showing the principal operating parts. 25 Fig. 2 is a vertical transverse section on the line 2 2, Fig. 1. Fig. 2^a is a partial vertical section on the line 2^a, Fig. 2, omitting the guide and support 45 46. Fig. 3 is a vertical longitudinal section, showing the adjusting devices 30 in side elevation. Fig. 4 is a vertical section transversely to the car on the line 4 4, Fig. 3. Fig. 5 is a detail elevation, showing the suspension device for regulating the maximum force of the brakes by the weight of the car. Fig. 35 6 is a horizontal section of the same on the line 6, Fig. 5. Fig. 7 is a vertical section on the line 7, Fig. 5. Fig. 8 is a vertical section on the line 8 8, Fig. 5. Fig. 9 is a plan view, illustrating a modification of the device shown 40 in Figs. 5 and 6. Fig. 10 is an enlarged detailed view of the releasing device of the emergency-brake hereinafter described. Fig. 45 11 is a longitudinal section of the same on the line 11, Fig. 10.

50 The draw-bar 1 is connected by the pitman 2 to the motor-lever 3. The motor-lever 3 and

operating-lever 4 are upon a common center, and are superimposed one over the other. They swing in parallel horizontal planes and engage, when approaching, by the contact of 55 projecting lugs 5 and 6 upon their approximate faces near their ends. The motor-lever 3 is actuated by the draw-bar. The operating-lever 4 is attached to the brake-chain 7, and pulls upon it when it is swung by the motor-lever. The operating-lever is kept in its plane 60 of rotation by a guide or adjusting bar, 45. (Shown in Fig. 3.) The reversal of adjustment is effected by the depression of this adjusting-bar, which carries with it the operating-lever, thus permitting the motor-lever to pass 65 it and take a position in which the movement by the draw-bar, which can bring the levers into engagement, is reversed.

Fig. 1 shows the principal parts of the apparatus as they may be placed upon the car. 70 8 is a transmitting equalizer-lever, to which the brake-chain 7 is attached by two branches passing in the form of a loop over a pulley, 9. By this device, in whichever way the operating-lever pulls, the brake-chain draws upon the 75 brakes. From the lever 8 a rod, 10, extends to the special brake-fittings which may be used. For illustration, an arrangement is shown in which the car is supplied with brakes upon 80 both trucks, and has the brake-shoes hung between the wheels. The chain connecting the two sets of brakes is carried through an equalizing-lever, 11, suspended under the center of the car. It extends from one brake-lever over 85 a sheave in the top of the companion lever, and thence to the equalizer. The rod 10 is attached to the equalizer, and when drawn will swing the equalizer and effect an application 90 of both sets of brakes. At one end of the equalizer is attached a take-up rod, 14, which is provided with a slot, 16, in which the pin connecting them works, and with a spring for keeping said take-up in its proper position. The take-up rod is serrated upon its edge and 95 rides over or against a tooth, 15, having a sharp edge for catching in the serrated edge of the bar.

It will readily be seen that when the equalizer is swung for applying the brakes it will 100 slide in the slot to its full length and then crowd the bar 14 over its catch 15. When the

brakes are released the equalizer swings back only as far as the length of the slot, and is then held. By this means a fixed limit is determined for the distance which the brake-shoes may hang from the wheels.

- 5 The rod 10 is continued through the equalizer and beyond to a spring, 18, and has a serrated edge, 17, which is set against catches 19 by the spring 20 in the end of the equalizer.
- 10 When the rod 10 is drawn in applying the brakes it effects a compression of the spring 18, and when the brakes are let off, if the equalizer is withheld from returning to its first position by the action of the take-up 14, the 15 tension of the spring 18 will draw the bar 10 through the opening in the end of the equalizer and make its working length correspond to the changed position of the equalizer. By the combined action of these take-ups the action 20 of the whole apparatus is unaffected by the wear of brake-shoes, and the parts are always in position to work with uniform stresses and a definite extent of movement. The hand-brake shaft 21 is connected, by its chain 22, 25 to the lever 8, as is also the chain 23 23^a of the emergency-brake. This part of the mechanism is a length of chain which passes through an eye or ring, 24, firmly set in the under side of the end sill, and which has a 30 ring or loop in its end 25, which may be thrown over a pin or hook upon the next car. In case that the coupling-link between the cars is broken while the train is running, the chain 23 23^a will be drawn out, and thereby effect an 35 application of the brakes. At a suitable place in the line of the chain 23 23^a is placed a coupling, 26, as shown in Figs. 10 and 11, which, when drawn into the ring on the end sill, will hook the chain to it, and at the same time, by 40 the contact of the inclined faces of the hooks 26^a with the interior of the ring 24, will automatically sever the end 23^a of the chain, so that it may be taken away upon the other car without breakage. The application of the 45 brakes upon the head car of the detached part of the train affords the resistance necessary to secure the instant application of the momentum-brakes upon all the cars so detached, and thus prevent the possibility of these cars running 50 into the other part of the train.
- The lever 8 is fulcrumed in the head of a bolt or rod, 30, which passes through the bolster to a connection with a bell-crank, 31. The horizontal arm of this crank has a pitman, 32, passing 55 down to a connection with two levers, 33, which levers are extended down to a position over the springs 34, which support the weight of the car. The fulcrums of these levers 33 are between the springs and the pitman, and are 60 so distanced as to secure that degree of multiplication of power which may be desired, as explained hereinafter. The arrangement and location of the levers 33 are not limited to those shown. They may be in the form of cranks, as 65 given in Fig. 6, or they may run in a direct line, as shown in Fig. 7. Again, they may be

put between the car and truck bolsters, instead of between the truck-timbers, as illustrated in Fig. 6.

Ordinarily the proportions set in the arrangement of the system of levers will probably be such as to make a braking stress of one-half the weight upon the wheels, and then any excess will find relief by raising the car upon the levers 33. If a higher rate of braking stress is desired, the connecting-point of the chain 7 with the lever 8 can be changed, and any desired rate of braking stress be thus established.

It will be seen readily that there is secured an arrangement which, without the use of relief-springs, gages at all times with any weight of load in the car a braking stress which is in a fixed proportion to the weight upon the 80 wheels.

Fig. 4 shows the arrangement of struts 41, connecting the balanced brake-beams with the balancing-levers 40, which are represented as being pivoted above the car-bolster at equal distances from the center. Fig. 3 shows a section of the same. At the center is placed a pitman, 42, which is to actuate the adjusting device. 40 are the balancing-levers; 41, the struts or pitmen of the same; 42, the pitman for effecting the adjustment; 43, a shaft bearing two crank-arms, one, 44, for the pitman 42, and the other, 44, in the line of the adjusting bar 45. 42^a may represent a slotted hanger.

The adjusting-bar 45 is held in two hangers, 46, bolted to the stringer of the car. Slots 47, through which it passes, are longer than the width of the bar, so that the bar can be depressed. The bar has at the points of supports diagonal slots 48, through which the supporting-pins 49 pass. A long slot, 50, in the bar receives the operating-lever 4. The bar 45 is held to the right by a spring, 51. At the right-hand end of the bar it has a cam-shaped finish, against which the arm 44 presses whenever the brake-beams change their position by the change in direction of wheel rotation. The swing of this arm 44 compels the adjusting-bar 45 to move toward the left. In doing so the action of its cam-slots upon the pins 49 compel it to be depressed and take with it the operating-lever 4, thus permitting a reversal of position by the levers 3 and 4. The lever 3 is confined in its plane of rotation by the bar 53. If it is desired to hold the apparatus in a position of disengagement, a brakeman turns the lever 54, which may be at any place upon the car, and thereby pulls the cord or chain 55, and with it the adjusting-bar, into the position that holds the operating-lever permanently out of engagement.

The operation of the apparatus is as follows: When the train has been made up with the levers in a position of disengagement, (or preferably so,) the related positions of the balanced brake-beams and the levers 3 and 4 may or may not be such that they will have proper coincident movements and changes. To se-

cure their correct adjustment, a brakeman will apply for an instant the hand-brake, which effects the setting of the brake-beams in the direction of wheel rotation. Then, if it is not 5 already done, he will turn the disengaging-lever and leave the operating-lever in position for engagement. Thereafter, regardless of the direction in which the car may be running, the transformations of the apparatus are purely 10 automatic, and will continue as needed until there may be an engine attached to the other end of the car, when the attention and service of a brakeman will be again required, as just described. Assuming that the car is running 15 forward, the motor-lever is before the operating-lever, and the pulling out of the draw-bar does not affect the brakes. Slow the engine, and the momentum of the train will compel a compression of the draw-bar and the swinging 20 inward of the motor-lever. This carries the operating-lever before it, and, by pulling upon the chain 7, swings lever 8 and pulls on the brakes. When the intensity of the brake application is equal to, say, one-half the weight 25 of the car on the wheels, the fulcrum of the lever 8 becomes the more yielding of the two ends of it, and the rod 30 is pulled out, relieving the brake stress. The rod 30 pulls upon the levers 33 and raises the body of the car in 30 a proportionate degree. The importance of this fulcruming of the braking stress against the weight of the car will be appreciated from the fact that the draw-bar movement is a definite one, and is actuated by the momentum of 35 the train behind the car rather than by the momentum of the car under consideration. This car may be light, while the train may be very heavy, and so, without this system of fulcruming, to avoid sliding the wheels it would 40 be necessary to so set the brakes as to never have a braking stress greater than that which an empty car could bear. This would sacrifice much of the power for operating brakes, which is represented by the great momentum 45 of the train and the increased weight of the car when loaded. The compression of the draw-bar being continued until the train is stopped, the engine, being backed, occasions a rotation 50 of the wheels in a reversed direction. This shifts the brake-beams, and they, in changing, depress the operating-lever, permitting the motor-lever to pass it, and then work free while the backing is continued. While backing, should the engine be slowed, the momentum of

the cars will pull out their draw-bars. This 55 brings the motor-lever into engagement with the operating-lever and applies the brakes, and the action of the mechanism continues, as before detailed.

Having thus described my invention, the following is what I claim as new therein and desire to secure by Letters Patent:

1. In a draw-bar brake apparatus, the combination of two sets of equalizing-levers, the one having the direction of its stresses in the 60 direction of the car's length and the other having the direction of its stresses in the direction of the car's weight, the first set being fulcrumed movably upon connections with the second set, and such connections serving to 65 transmit the stress of one set of equalizers to the other when the intensity of brake application equals a given proportion to the car's weight, thereby relieving the braking stress, substantially as and for the purposes specified. 70

2. The equalizer - levers 33 and carrying-springs 34, said levers having fulcrums or short arms between the said carrying-springs and the truck-bolster, substantially as and for the purposes set forth. 75

3. The combination of the transmitting-equalizer 8 with the chains 7, 22, and 23, each being connected with a separate motor element, for applying the brakes.

4. The combination, with an equalizing brake-lever, 11, of the take-up devices 14 and 17 18 19 20, substantially as set forth. 85

5. The combination of the emergency-brake 23 24 25 26 with a momentum-brake.

6. The adjusting-bar 45, controlling the operating-lever 4, having cam - slots for raising or depressing it when moved endwise. 90

7. The combination, with the lever 4, of the adjusting-bar 45, engaging - spring 51, guides 48 49, and the disengaging cam-movement 44, 95 as set forth.

8. The combination of the obliquely-slotted adjusting-bar 45, slotted hangers 46, and pin 49, substantially as and for the purposes set forth. 100

9. The combination, with the brake-beams, of the pitmen 41 42, shaft 43, crank - arms 44 44', and adjusting-bar 45, substantially as and for the purposes set forth.

DOLPHUS TORREY.
